UNITED STATES PATENT OFFICE.

JOSEPH R. MAHAN AND JOHN B. PICARD, OF TOLEDO, OHIO, ASSIGNEES TO THE NATIONAL SUPPLY COMPANY, OF TOLEDO, OHIO, A CORPORATION OF OHIO.

DRIVING MEANS FOR ROTARY DEVICES.

Application filed April 18, 1927. Serial No. 184,577.

Our invention relates to driving means for rotary devices. The invention is illustrated and described in connection with means for driving eccentrics used in operating pumping mechanisms, but it is not limited either to eccentrics or pumping mechanisms.

In pumping powers for wells, one or more horizontal eccentrics are strung on a vertical 10 spindle. A driving wheel is also strung on the spindle and rests on the top eccentric. The driving wheel and eccentric or eccentrics are connected into a rigid unit by means of vertical bolts which pass through holes in 15 the same. Also the driving wheel has a driving arm which interlocks with the eccentric next below it, and, in case there are two eccentrics, the top eccentric has a driving arm which interlocks with the lower 20 eccentric, it being intended that the bolts and the driving arm or arms shall take proportionate parts of the torsional strains required to drive the eccentric or eccentrics.

It is one object of this invention to provide 25 adjustments whereby the bolts and driving arms may be made to do their proportion of the work. Another object is to construct and arrange the adjusting means so that they will, in addition to their function of making 30 and securing the adjustment mentioned, take a portion of the lateral strains exerted transversely of a vertical plane in which the bolts stand. Another object is to provide means for greatly relieving the driving arm 35 or arms from vertical downward strains due to the downward movement of the adjusting wedges which bear thereon. The wedges take the up thrust of the arm or arms when the unit tends to tilt in a direction opposite 40 to that in which the arm or arms extend.

This invention is an improvement on the structures shown in Schwimmer and Wright's Patents 1,612,989 granted January 4, 1927 and 1,648,066 granted Nov. 8, 1927.

Referring to the accompanying drawings, 45 Fig. 1 is a horizontal cross-section on the line 1—1 of Fig. 2, parts being broken away; Fig. 2, a central section taken in the vertical plane in which the bolts 11 and 12 stand, portions at the top and sides being broken away; Fig. 3, a section on the line 3—3 of Fig. 1; and Fig. 4, a section on the line 4—4 of Fig. 1.

On the drawing, 1 designates a vertical 50 spindle having the base 2 on which rests the

friction ring 3 encircling the spindle. The bushing 4 surrounds the spindle and has the flange 5 seated on the said ring. The eccentric 6 is mounted on the bushing 4 and rests on the flange 5 and carries the eccentric strap 7.

On the top of the eccentric 6 rests the eccentric 8 also mounted on the bushing 4 and carrying the eccentric strap 9. The driving member 10, which may be the lower 65 part of a band-wheel or other driving wheel rests on the eccentric 8 and embraces the said spindle 1.

The said two eccentrics 6 and 8 and the driving member 10 are tightly clamped together into a rigid unit by the two bolts 11 and 12 arranged parallel with the spindle 70 and on opposite sides thereof.

The driving member 10, whether band-wheel or gear wheel, has the horizontally-extending driving arm 13 preferably cast integrally therewith. The outer or free end of the arm 13 lies between two upstanding lugs 14 on the eccentric 8, the opposing faces of which lugs are vertical or parallel 75 with the axial center of the eccentric 8. The lateral edges of the arm 13 diverge downwardly. Wedges 15 are seated between each lug 14 and the nearest inclined edge or face of the arm. The ends 16 of the 80 wedges next to the lugs are parallel with the faces 17 of the lugs they engage, and the ends 18 of the wedges engaging the inclined faces 19 of the arm are inclined to fit the said faces. The wedges are drawn down 85 tightly between the arm 13 and the lugs 14 by the bolts 20 which have their heads 21 engaging the bottom of the eccentric and their nuts 22 engaging the tops of the 90 wedges.

The eccentric 6 has diametrically opposite the arm 13 an arm 13^a whose outer end lies between two lugs 14^a engaged by the wedges 15^a which are operated and held in place by the bolts 20^a, the lugs 14^a being on the upper 95 face of the eccentric 6. It is not necessary to describe the parts 13^a, 14^a, 15^a and 20^a as they are like the parts 13, 14, 15, and 20, respectively, and provide the same connections and functions between the two eccentrics as are provided between the upper 100 eccentric 8 and the member 10.

In devices of the character described it is desirable that the bolts 11 and 12 by their reaction to shearing carry a proportionate 110

share of the torque through the several parts of the unit connected together by them. This is done by rotating the eccentrics and driving member 10 so that all lost motion between the bolts and the holes they are in is all taken up in the direction in which the eccentrics and driving member rotate in practice. The bolts engage the sides of the holes as shown in Fig. 1, the rotation being 10 in the direction shown by the arrow. In Fig. 1, the left-hand wedge 15 will be first tightly seated; then the right-hand wedge will be secured tightly in place. Also the right-hand wedge 15^a will be secured in place before the left-hand wedge. The opposing faces of the lugs 14 and 14^a are made vertical or parallel with the center of the spindle 1 so as not to change the relation of the bolts to the parts through which they pass, as the 20 wedges are forced downwardly.

The opposing faces of the lugs 14 and 14^a are made arc-shaped so that the wedges may adjust themselves by sliding on those faces to fit squarely against the arms 13 and 13^a.

25 It will be noted particularly in Fig. 4 that the arm 13 rests at opposite sides of the wedges, upon machined surfaces on the two rests 23 and 24 on the eccentric 8. These rests prevent downward strains tending to 30 weaken or break the arm 13 off from the member 10. The arm 13 together with the wedges 15 resist tilting strains exerted between the eccentric and member 10 at right angles to a vertical plane which includes 35 the bolts 11 and 12. The two bolts 11 and 12 resist to a large extent tilting strains exerted in a vertical plane in which the bolts stand.

The lower eccentric 6 will have rests (only 40 one, 23^a, shown) for the arm 13^a.

We claim—

1. A rotary driving element, a rotary driven element, an arm projecting from one element, a pair of lugs carried by the other 45 element and having the arm between them, and wedging means seated against the lugs, and clamping the arm to the element not bearing the arm and preventing the arm from moving toward one of the lugs.

50 2. A rotary driving element, a rotary driven element, an arm projecting from one element, a pair of lugs carried by the other element and having the arm between them, arm-supporting means on the element not bearing the arm, and wedging means having 55 reaction against the lugs, clamping the arm against the arm-supporting means and preventing the arm from any movement independent of the movements of the said 60 elements.

65 3. A rotary driving element, a rotary driven element, an arm projecting from one

element, a pair of lugs carried by the other element and having the arm between them, bolts clamping the said elements together, 65 there being aligned bolt holes in the said elements for the said bolts, and wedging means operating on the arm to take up any slack between the sides of the bolts and the holes they occupy and prevent movement of the 70 arm away from the element not carrying the arm.

75 4. A rotary driving element, a rotary driven element, an arm projecting from one element, a pair of lugs carried by the other element and having the arm between them, arm-supporting means on the element not bearing the arm, bolts clamping the elements into a unit, and wedging means cooperating 80 with the arm and the lugs for binding the arm against the said supporting means and for preventing the arm from moving toward either lug and for causing all slack between the sides of the bolts and the holes they occupy to be taken up in the direction of rotation of the elements.

85 5. In a pumping power, a vertical spindle, superposed eccentric and driving members rotatable around the spindle, spaced lugs on one member, an arm carried on the other member and lying between the lugs, the arm having opposite edges converging upwardly, wedges seated against the opposing faces of the lugs and having inclined surfaces resting on the said converging edges, 90 bolts clamping the said members together, and two other bolts, one acting on one wedge to cause all slack between the sides of the bolts and the holes they occupy to be taken up in the direction of rotation of the members, and the other acting on the other wedge to hold it in place.

95 6. In a pumping power, a vertical spindle, superposed eccentric and driving members rotatable around the spindle, spaced lugs on one member, an arm carried on the other member and lying between the lugs, the arm having opposite edges converging upwardly, wedges seated against the opposing faces of the lugs and having inclined surfaces resting on the said converging edges, rests for the 100 arm, carried by the member not bearing the arm, bolts clamping the said members together, and two other bolts, one acting on one wedge to cause all slack between the sides of the bolts and the holes they occupy to be taken up in the direction of rotation of the members, and the other acting on the other wedge to hold it in place.

105 In testimony whereof, we hereunto affix 110 our signatures.

JOSEPH R. MAHAN.
JOHN B. PICARD.
